PORATION OF NEW YORK.

SPRING CONTROL.

Application filed June 23, 1927. Serial No. 200,802.

Our invention relates to improvements in spring controls, so-called, in which a spring is arranged so that under certain conditions it will operate on a connected part to perform certain work. Controls of this type are used in automatic vehicle stops acting when released to operate brakes, cut out ignition or operate audible or visible signals. Our invention is intended to produce a simple, reliable spring control of this character which is particularly well adapted for use in connection with automatic vehicle stops and which is also adapted for other uses.

In carrying out our invention, we have the main or operating spring arranged in a casing which really acts as a link as well as a support for the spring, and its connected parts, and when the spring is taut or under tension, it is held in this position by a toggle joint aligning when extended with the axis of the spring and its connected parts, and when the joint is broken, that is flexed, it permits the spring to react and perform its work.

Our invention is also intended to provide a simple magnet, operated means for breaking or flexing the toggle joint, and further to provide means in connection with the operation of the apparatus for controlling an electric circuit which may operate on the ignition of the car, the visible or audible signals or do other work. In general our improvement is intended to provide a simpler and better means for accomplishing the foregoing results than has heretofore been used for the purpose.

Reference is to be had to the accompanying drawings in which similar reference characters represent the corresponding parts in all views.

Figure 1 is a plan view of the gun embodying our invention.

Figure 2 is a longitudinal section on line 2-3 of Figure 1 with the main spring compressed.

Figure 3 is a section on the line 2-3 of Figure 1 showing the main spring extended, and

Figure 4 is a bottom plan of the device. The device or apparatus is provided with a frame or casing 10 which is preferably rectangular and open at top and bottom. At one end it is shown connected with a rod

11 and at the other it connects with a rod 11' which slides through the end of the casing. Thus the casing acts like a link connecting the parts 11-11' of a rod which may be a brake rod so that when the spring is released to extend itself it will act to virtually shorten the brake rod and pull on the end 11'. Obviously the rod pulling on the shortening part of the mechanism of the casing frame or link 10 can be made to do other work. The inner end of the rod 11' connects with an abutment 12 which slides in the casing 10 and which can be conveniently of U-shape having side ears 13 which facilitate its connection to the toggle arms or levers presently referred to. Between the abutment 12 and one end of the casing 10 and coiled around the rod 11' is a main spring 14 which normally presses the abutment towards the rod 11. The abutment 12 connects with a toggle joint which is arranged to align with the rod parts 11-11'. This joint is shown as comprising arms or levers 15 and 16 which are pivoted together by the pin 17, and the arms 16 are pivoted in the casing as at 18, while the outer ends of the arms 15 are connected by a pivot pin 19 with the ears 13 on the abutment. Thus when the spring 14 is compressed, the toggle joint will be in its straightened position in alignment with the spring and the rod parts 11-11' thereby holding the spring against expansion, but when the joint is broken or flexed, as in Figure 3, the spring can expand and thus pull on the rod 11' or in other words shorten the composite rod 11-11'.

The toggle joint is flexed by means of a link 21 which is pivoted to the member 17 of the joint to provide for the expansion of the spring. The casing is slotted as at 20 to permit the pin 19 to slide lengthwise of the casing. One end of the link 21 connects with a slide block preferably comprising spaced members 22, the connection being by means of a pin 23 which has a slightly sliding movement in the slot 24 of the slide block and which also can slide in the slot 25 of the casing. The slide block 22 is held in the position shown in Figure 2 by a light spring 26, and is moved against the tension of the spring by the core 26' of a solenoid magnet 27. It will be seen that when the magnet is energized it will pull on the core 26' and on the outer end of the link 21 thereby mov-

ing the link to the position shown in Figure 3 and breaking or flexing the toggle joint so that the spring 14 can instantly expand. In automatic car stops, the circuit through the magnet 27 is usually closed by the action of a bumper or the like, but so far as our present invention is concerned, it may be closed in any way. As a convenient means of connecting the magnet, we have shown it provided with contacts 28 and 29 connected to a block 31, and with wires 30 connecting the contacts through the block to a conventional connector 32. The block 31 can be an ordinary plug. We have shown a third pair of contacts 33 which connect with the connector 32 as usual and one of which connects by a wire 34 with a contact 35 on the opposite end of the magnet being suitably insulated thereon. This contact 35, when the spring 14 is compressed, connects with an insulated pin 37 carried by the part 13, and which may be included in an ignition or other circuit. The part 35 may obviously be arranged in other ways to make and break a circuit. When the spring 14 is compressed, as it is normally, the ignition or other circuit is closed, but when the spring is released and expands, the pin 37 is moved away from the contact 35 as in Fig. 3 and the circuit is broken.

From the foregoing description, it will be seen that the device which we have shown is very strong, practical and simple. The rod 11' is pulled out mechanically, usually by some form of lever to compress the spring 14 and this straightens out the toggle joint, that is the levers 15 and 16 and when these are straight, the spring will be positively held against compression. When, however, the magnet 27 is energized, the joint is broken or flexed in the manner already described, and the spring immediately reacts to pull on the rod and thus actuate any part connected with it, and also break the circuit which includes the contact 35 and pin 37. Obviously other means than that shown can be used for closing the circuit through the magnet, and our invention is not limited to any particular circuit closing means, neither is it limited to the precise means for breaking or flexing the toggle joint, although we have shown a way which we believe to be good and which we believe also to be novel.

We claim:

55. 1. A spring control, comprising a casing connected at one end to a rod and at the opposite end to a second rod which slides in the casing, a spring acting to move the slide rod, a toggle joint coupled to the slide rod and acting when straightened to hold the spring compressed, and means for flexing the toggle joint.
60. 2. A structure of the kind described, com-

prising a casing adapted to connect with a support, a slide rod entering the casing, a spring to move the slide rod, a toggle joint acting to lock the rod for holding the spring compressed, and electromagnetic means for flexing the toggle joint.

3. A spring control, comprising a casing connected to a support, a slide rod entering the casing, a spring acting to pull the slide rod inward, a toggle joint connecting the casing with the slide rod, and means for flexing the toggle joint.

4. A spring control, comprising a casing connected to a support, a slide rod entering the casing, an abutment on the slide rod, a spring coiled around the rod between the abutment and the part of the casing, a toggle joint connecting the abutment with the casing, and means for flexing the toggle joint.

5. A spring control, comprising a support, a slide rod movable on the support, a spring for actuating the slide rod, a toggle joint connecting the slide rod with the support, and means for flexing the toggle joint.

6. A spring control, comprising a support, a slide rod mounted on a support, a spring for actuating the slide rod, a toggle joint connecting the slide rod with the support and acting to hold the spring compressed, means for flexing the toggle joint, an electric circuit, and means operated by the movement of the slide rod for controlling said circuit.

7. A spring control, comprising a support, a slide rod movable on the support, a spring for actuating the slide rod, a toggle joint connecting the slide rod to the support, a link connected with the middle portion of the toggle joint, and an electromagnet for moving the link and flexing the toggle joint.

8. A spring control, comprising a support rigidly connected to one rod and slidably connected to a second rod aligning with the first rod, a toggle joint connecting the second rod with the support, a spring for actuating the second rod, and means for flexing the toggle joint.

9. A spring control, comprising a support rigidly connected to a rod and slidably connected to a second rod, a main spring coiled around the second rod and acting to move it in one direction, a toggle joint connecting the second rod with the support, a link connected to the toggle joint, and an electromagnet for pulling on the link and flexing the toggle joint.

In testimony whereof, we have signed our names to this specification this 21st day of June, 1927.
